UNITED STATES PATENT OFFICE.

WILLIAM W. BIRNSTOCK, OF YORK, PENNSYLVANIA, ASSIGNOR TO YORK MILK MACHINERY COMPANY, OF YORK, PENNSYLVANIA, A CORPORATION OF PENNSYLVANIA.

BOTTLE CRATE.

Application filed April 16, 1923. Serial No. 632,493.

To all whom it may concern:

Be it known that I, WILLIAM W. BIRNSTOCK, a citizen of the United States, residing at York, in the county of York and State 5 of Pennsylvania, have invented certain new and useful Improvements in Bottle Crates, of which the following is a specification.

The present invention relates to improvements in bottle crates, and more particularly 10 to those of the kind suitable for use in the handling of milk bottles.

The primary objects of the invention are to provide a novel and improved crate structure, whereby the bottles will be effectually 15 supported in their proper position within the crate, whether the bottles be inserted therein in upright or inverted position, certain parts of the crate structure may be used interchangeably in the manufacture of 20 crates for different sizes and numbers of bottles, thus standardizing the crate structures, and thereby facilitating their assembling and otherwise reducing their cost of manufacture, and furthermore, the crates 25 may be used conveniently and efficiently as containers for the bottles when the latter are passed, while in inverted position, through a bottle washing machine.

To these and other ends, the invention 30 consists in certain improvements and combinations and arrangements of parts, all as will be hereinafter more fully described, the features of novelty being pointed out particularly in the claims at the end of the specification.

In the accompanying drawings:

Figure 1 is a top plan view of a milk bottle crate constructed in accordance with one embodiment of the invention;

Figures 2, 3 and 4 are top plan views of portions of milk bottle crates constructed in accordance with the present invention to accommodate, respectively, bottles of different sizes;

Figure 5 represents a vertical section through the crate shown in Figure 1, the section being taken on the line 5—5 in that figure;

Figures 6, 7 and 8 represent vertical sections on the lines 6—6, 7—7 and 8—8, respectively, in Figures 2, 3 and 4; and

Figures 9, 10, 11 and 12 are detail perspec-

tive views of the bottle-supporting cups, as shown in Figures 5, 6, 7 and 8 respectively.

Similar parts are designated by the same 55 reference characters in the several views.

The present invention provides improvements in bottle crate structures which are applicable more particularly to crates of the kind adapted for use in the handling of milk 60 bottles, both when filled and empty, the invention providing novel and improved means for supporting the bottles in upright position, when filled, and in inverted position when empty, the bottles, when in inverted position in the crates, being ready for washing by passing them while in the crates through a bottle washing machine. The preferred embodiments of the invention 65 are shown in the accompanying drawings 70 and will be hereinafter described in detail. It is to be understood, however, that the invention is not restricted to the precise constructions shown, as equivalent constructions 75 are contemplated and these will be included within the scope of the claims.

According to the present invention, as shown in the present instance, each crate comprises a pair of end walls or members 1 and a pair of side members 2, these members being suitably joined or united at their corners to form a substantially rectangular case of appropriate size, longitudinal cup-supporting members 3 which extend across the bottom of the crate, in pairs and are secured 80 by pins, nails or other suitable devices 4 to the respective end members of the crate, and bottle-supporting cups which are mounted on and secured to the respective pairs of members 3. Partition members 5 which may 85 be of any suitable kind and number preferably extend both longitudinally and transversely of the crate, at appropriate levels above the bottle-supporting cups and secured at their ends in the end and side members respectively of the crate. The cup-supporting members 3 may be of any suitable cross-section, although it is preferable to construct them of flat strips, the intermediate portions of which have their flat sides 90 arranged vertically, and the ends of which are twisted to bring their flat sides into a horizontal plane and thus facilitate their attachment to the end members of the crate, 95 100

2
this construction being particularly advantageous when the lower edges of the end members 1 are provided with strips 1^a which are secured in place by nails or similar means 6, the flat twisted ends of the cup supporting members 3 being then adapted for interposition between the respective strips 1^a and the body portions of the end members 1 and having perforations through 10 which the securing devices 4, such as nails, may be driven.

Each pair of longitudinal members 3 serves to support a set of bottle-supporting cups. The number of cups on each pair of 15 these members may vary according to the size and the number of bottles to be accommodated in the crate, but it is advantageous and generally preferable to construct the cups for bottles of different sizes, 20 so that they will be received interchangeably on pairs of the members 3 which are spaced the same distance apart. It is also advantageous and generally preferable to construct the bottle-supporting cups of different sizes so that their means for securing 25 them upon the pair of supporting members 3 are similar and uniform in construction, certain advantages and economies in manufacture thereby being effected, as will hereinafter appear.

In the crate shown in Figure 1, which is adapted to accommodate one dozen milk bottles of relatively large size, as for example, the quart size, three pairs of cup 35 supporting members 3 are provided within the crate and each pair of these members has a set of four bottle-supporting cups 7 fixed thereto. Each cup in this instance, and as shown in detail in Figures 5 and 9, 40 comprises a flat body 8 having upturned concentric segmental ears or flanges 9 at its corners, a central opening 10, a surrounding substantially concave depression 11, and a pair of lugs 12 which are cut from the body 8 at diametrically opposite points and are bent down, as shown in Figures 5 and 45 9. The cup is preferably produced from a punching of sheet metal, its substantially flat portion 8 with the marginal segmental ears 9 providing a socket or seat to receive and hold the bottom of a milk bottle in 50 centered position thereon, as indicated by the dotted lines in Figure 5, and the depression 11 provides a socket to receive the mouth of a milk bottle when inserted into the crate 55 in inverted position, the bottle being thereby supported and held centered by said depression in the cup. The downturned ears 12 at diametrically opposite sides of the cup 60 are so positioned that they will straddle the supporting members 3, to which these ears may be suitably fixed, as by welding, riveting or the like, the downwardly bulged central portion of the cup, produced by the 65 depression 11 being accommodated in the

space between the supporting members 3, as clearly appears in Figure 5.

In constructing crates to accommodate milk bottles of smaller sizes, the spacing between each pair of cup-supporting members 3 may be the same as is the case where the cups for the larger size bottles are used, but an additional pair of cup-supporting members can be accommodated within the 70 crate and also a greater number of bottle 75 supporting cups may be provided on each pair of cup-supporting members. As shown in Figures 2, 3 and 4, four pairs of cup-supporting members 3 are used and they are uniformly mounted within the crates, notwithstanding that the size of the bottles to be received varies, and by spacing the cups more closely on each pair of supporting members, the number of bottles to be accommodated by these crates can be increased. The cup-supporting members 3, 80 however, may be constructed and secured within the crate, substantially as shown and described with respect to the crate illustrated in Figure 1, the spacing between the 85 supporting members of each pair being uniform, although the pair of supporting members are located more closely within the 90 crate.

The bottle supporting cups employed in 95 the crates shown in Figures 2, 3 and 4 and which, as shown, are adapted to accommodate milk bottles of pint, one-half pint and one-quarter pint sizes, respectively, are shown in Figures 10, 11 and 12, respectively, 100 these cups being interchangeably attachable to any pair of cup-supporting members 3. The cup shown in Figure 10, which is preferably formed from a stamping of sheet metal, 105 comprises a body 8^a having concentric segmental ears or flanges 9^a at its corners, so that this body portion provides a seat or socket to receive, support and center the bottom of a bottle, as is shown by the dotted lines representing the upright bottle in Figure 6, and the cup contains a central opening 10^a surrounded by a concave depression 11^a, this depression being of a size and shape 110 to receive, support and center the mouth of an inverted milk bottle, as is indicated by the dotted lines in Figure 6 representing the inverted bottle. Ears 12^a formed at diametrically opposite sides of the body 8^a and bendable downwardly from the plane thereof provide attaching means for securing the cup to the longitudinal supporting members 3, these ears, when bent downwardly in substantial parallelism, being arranged to straddle the outer sides of the supporting members 3, as shown in Figure 6, and the depression 11^a being accommodated in the space between the supporting members. The ears 12^a may be welded, riveted or otherwise fixed to the supporting members. The 115 bottle supporting cup shown in Figure 11 120

and which is of the type used in the crate illustrated in Figure 3, may also be formed from a punching of sheet metal, it comprising a body portion 8^b which is flat or substantially so and has segmental ears or flanges 9^b at its opposite edges which are concentric and segmental, the body portion 8^b being thus adapted to serve as a seat or socket to receive, support and center the bottom of a bottle inserted in upright position into the crate, and the center of the cup has an opening 10^b which is surrounded by a concave depression 11^b, this depression being of a size and shape to receive, support and center the mouth of a bottle inserted in inverted position within the crate. Diametrically opposite edges of the body 8^b have ears 12^b projecting therefrom, these ears being bent downwardly into substantial parallelism so that when the cup is applied to the longitudinal supporting members 3, these ears straddle the outer sides of such members and may be welded, riveted or otherwise suitably fixed thereto, the depressed portion 11^b of the cup being accommodated between the supporting members 3, as is shown in Figure 7. The cup shown in Figure 12 is of the kind preferably used in crates of the form shown in Figure 4, this cup being suitable for use in crates adapted to contain milk bottles of the one-quarter pint size, which commonly have the bottom and mouth of the same diameter and substantially of the same shape. The cup in this instance, which may be formed from a punching of sheet metal, comprises a body 8^c having ears 12^c projecting from diametrically opposite edges thereof and bent downwardly, the cup has a central opening 10^c and it also has a concave depression 11^c which surrounds the opening 10^c within the body 8^c and is of a size and shape to receive, support and center the bottom of an upright bottle or the mouth of an inverted bottle. The cup in this instance is applicable to the longitudinal supporting members 3, as in the previous instances, the downturned ears 12^c being so positioned that they will straddle the outer sides of these supporting members and are adapted to be welded, riveted or otherwise secured thereto, and the depressed portion 11^c of the cup will be accommodated in the space between the supporting members. By providing pairs of supporting members to which the sets of individual bottle supporting cups are secured, the crates may be advantageously assembled from parts which are interchangeable in the different crates, and by constructing the different size cups so that they are all applicable to uniformly-spaced pairs of supporting bars, the operations incident to the application and fastening of the different cups to these bars may be performed with facility and at relatively small expense. The struc-

ture is such that the crates, which are all of the same size, may be readily constructed to accommodate bottles of different sizes and numbers, the individual cups in each instance being securely supported by the respective pairs of supporting members, and the cups functioning to properly support, center and hold the bottles in proper position within the crate. The central openings in the cups serve to admit jets of water or other washing agents to the mouths of the bottles when the crates containing the bottles in inverted position therein, are passed through a bottle washing machine of appropriate construction.

By constructing the cups individually for the different bottles, they may be produced inexpensively, and by mounting and securing the individual cups on the pairs of uniformly-spaced supporting members, as hereinbefore described, the assembling of these parts may be accomplished inexpensively and with facility.

The present invention provides a crate structure which is particularly advantageous where the bottles are filled and capped while they are contained in the crates, thus, for example, meeting the growing tendency of dairymen to fill and cap milk bottles as the latter come from the washing machine, thus avoiding the loss of time and the labor of presenting the bottles, one at a time, to the filling and washing machine. According to the present invention, the crates to contain quart, pint, half-pint and quarter-pint bottles may each be constructed readily and inexpensively to contain the same number of bottles, say a dozen, and these bottles in the different crates may be spaced uniformly, this being capable of accomplishment inexpensively and with facility by reason of the individual bottle-cup structure hereinbefore described, the different crates, although constructed for bottles of different sizes, being thus adapted for filling and capping by an in-the-case filler. On the other hand, the individual bottle supporting cup construction enables the crates to be inexpensively constructed to accommodate different numbers of bottles, as may be permitted by the different sizes of the bottles, or to accommodate any desired number of bottles, this being particularly advantageous in constructing crates to contain beverage bottles.

I claim as my invention:

1. In a bottle crate, the combination with the outer casing, of members supported by said casing to extend in pairs across the bottom thereof, and a set of individual bottle supporting cups mounted on each pair of said members, each cup having parts which locate and secure it to its respective pair of supporting members.

2. In a bottle crate, the combination with

an outer casing, of a pair of supporting members extending across the bottom thereof, and a set of individual bottle supporting cups spaced longitudinally on said members 5 and having portions which straddle said members and secure the cups thereto.

3. In a bottle crate, the combination with an outer casing, of a pair of supporting members extending across the lower portion 10 thereof, and a set of bottle supporting cups mounted in longitudinally spaced relation on said member, each cup bridging said members and having lugs which respectively secure it to said members.

15 4. In a bottle crate, the combination with an outer casing, of a pair of supporting members having their ends secured to opposite walls of the casing, and a set of bottle supporting cups mounted in longitudinally 20 spaced relation on said members, each cup bridging said members and formed with bent ears which lap and are secured to the respective supporting members.

5. In a bottle crate, the combination of a 25 pair of parallel supporting members, and a set of bottle supporting cups arranged in longitudinally spaced relation thereon, each cup comprising a substantially annular body to receive and support a bottle, and having 30 ears at its opposite edges which are secured respectively to the supporting members.

6. In a bottle crate, the combination of a 35 pair of supporting members, and a set of individual supporting cups spaced longitudinally thereon, each cup comprising a sheet metal body shaped to receive and support a bottle and having at its opposite edges ears bent out of the plane of the body and secured to said supporting members.

40 7. In a bottle crate structure, the combination of a pair of supporting members, and a set of individual bottle supporting cups spaced longitudinally thereon, each cup having an inner depressed portion to receive and 45 support the mouth of a bottle, said depressed portion being accommodated in the space

between said members, and ears which straddle the outer sides of said members and secure the cup thereto.

8. In a bottle crate structure, the combination of a pair of supporting members, and a plurality of individual bottle supporting cups spaced longitudinally thereon, each cup having an inner depressed portion which is accommodated in the space between said members and is shaped to receive a portion 55 of a bottle to center and support it, and ears proceeding from opposite edges of the cup and bent downwardly at the outer sides of said members and secured to the latter.

9. In a bottle crate structure, the combination of a pair of substantially parallel supporting members, and a plurality of individual bottle supporting cups spaced longitudinally thereon, each cup comprising a body 65 having a seat which bridges said members and is adapted to center and support the bottom of a bottle, an inner relatively depressed portion which is accommodated in the space between said members and is adapted to center and position the mouth of a bottle, and ears which proceed from opposite edges of the 70 body and are bent out of the plane thereof to respectively engage said members and secure the cup thereto.

10. In a bottle crate structure, the combination of a pair of supporting members in substantial parallelism, and a plurality of individual bottle supporting cups spaced longitudinally thereon, each cup comprising 80 a body of sheet metal which bridges said members and is adapted to center and support the bottom of a bottle, an inner depressed portion which projects into the space between said members and is adapted to center and support the mouth of a bottle, and ears which extend from opposite edges of the cup and are bent to engage the outer sides 85 of said members to secure the cup thereto.

In testimony whereof I have hereunto set 90 my hand.

WILLIAM W. BIRNSTOCK.
